TRIMMING-MACHINE.

1,158,681.

Specification of Letters Patent.

Patented Nov. 2, 1915.

Application filed May 3, 1913. Serial No. 765,260.

To all whom it may concern:

Be it known that I, JOHN B. HADAWAY, a citizen of the United States, residing at Swampscott, in the county of Essex and 5 State of Massachusetts, have invented certain Improvements in Trimming-Machines, of which the following description, in connection with the accompanying drawings, is a specification, like reference characters on 10 the drawings indicating like parts in the several figures.

This invention relates to machines for trimming the edges of sheet material, and the particular object is to provide a machine 15 for trimming the edges of an insole after attachment of the latter to the bottom of a last in the process of manufacture of boots and shoes.

In the manufacture of some classes of 20 shoes, such as Goodyear welt shoes, in which the insole is tacked temporarily to the bottom of a last before the upper is secured thereto, it is important that the edges of the insole should lie flush with the edges of the 25 bottom of the last, especially at the forepart and heel, in order to insure a nice fit for the upper in the pulling over and lasting operation and provide a comfortable shoe of the desired shape and size. The insole is therefore cut to fit the last accurately; but prior to its attachment to the last it is 30 channeled and the channel lip or flap is turned back. The lip turning operation, and sometimes also the channeling operation, is 35 performed while the insole is in a dampered or "tempered" condition, and the effect is usually to stretch the insole lengthwise, so that when it is fitted accurately to the last at the forepart it will nearly always project 40 somewhat at the heel end. It is impracticable to allow for this stretching in cutting out the blank, since the effect varies greatly with different grades of stock and with different degrees of temper. To remedy the 45 difficulty it has been customary to trim off the projecting portion at the heel end with a hand knife. This expedient has been unsatisfactory for the reason that the operation is slow and the results are not uniform. Furthermore, in order to insure a better fit 50 for the upper materials, particularly if a molded counter is to be used, the edges of the insole at the heel end should be beveled

so as to provide a rounded surface over which the upper and counter may be lasted; 55 and hand workmen cannot be depended upon to take the pains to shape the insole in this manner.

The present invention provides a machine which, while capable of other uses, is particularly adapted to perform the trimming operation above described and secure uniform and accurate results. The machine comprises a driven cutter, preferably of the 60 rotary type, and guiding means upon which 65 to position the last so that the cutter will trim the insole accurately with reference to the lateral surfaces of the last. In the preferred embodiment of the invention the guiding means is so arranged in relation to 70 the cutter that the latter will cut through the insole in the general direction of the height of the last or in a direction from one face to the other of the insole, means being 75 also provided for supporting the edge of the insole in the path of the cutter and arranged with reference to the cutter to act as a shearing member in coöperation therewith. Such a machine will make a clean cut on the edge, and has also the important 80 advantage of performing the trimming operation without any tendency to stretch or otherwise distort the insole upon the last through the action of the cutter.

Another important object of the invention 85 is to arrange the cutter and guide, while maintained in the above described relation, that the last may present the insole in a substantially vertical plane during the trimming operation, which enables the 90 workman readily to observe the effect of the cutter and to manipulate the last with facility and accuracy.

Further features reside in means for positioning the last and insole with reference 95 to the cutter so as to secure the desired degree of bevel upon the edge of the insole, and in means whereby the workman is enabled to manipulate the last so as to trim inward farther toward the lateral surface 100 thereof at certain stages of the trimming operation.

The preferred embodiment also includes provision for adjustment of various parts of the machine, particularly with a view to 105 varying the depth of cut of the trimming

operation with reference to the lateral surfaces of the last and varying the degree of bevel.

Other and more particular features and objects of the invention will appear from the following detailed description.

In the accompanying drawings which illustrate a preferred embodiment of the invention; Figure 1 is a side elevation of the upper portion of the machine; Fig. 2 is a perspective view showing the front of the upper portion of the machine, a part of the cover over the cutter being broken away; Fig. 3 is a section on the line 3—3 of Fig. 1 showing also a portion of a last and an insole in operative position.

Bolted upon the frame 2 is a support 4, and journaled in suitable bearings in the frame and the support is a rotary shaft 6 which is inclined somewhat from the vertical toward the front of the machine for a purpose to be subsequently explained, and is driven by a belt 8 from a suitable source of power. Secured upon the upper end of the shaft is a cutter 10 which is frustoconical in form and tapers toward its upper end so that a line across the periphery of the cutter in the plane of the shaft at the front of the machine is substantially vertical. The cutter has cutting edges that extend across its periphery from end to end and are inclined to radial planes so as to have a shearing action on the stock. In the drawings the cutter is shown as arranged for rotation in a counter-clockwise direction, but it will be obvious that as far as concerns many features of the invention the direction of rotation of the cutter is immaterial and that it is within the province of the invention to employ a cutter arranged for rotation in the opposite direction.

The upper surface of the support 4 is inclined downwardly toward the front of the machine, and is provided with guideways 12 and 14 that receive downwardly projecting tongues formed respectively on bracket members 16 and 18. These members are adjustable up and down the guideways and are provided with bolts 20 and 22 respectively to clamp them securely to the support in their adjusted positions. The bracket 16 carries at the front a plate 24 provided with a curved portion 26 that is shaped to conform substantially to the periphery of the cutter and has at its forward end a lip 28 formed to project between the bottom surface of a last and the insole attached thereto. The lip 28 thus serves as a guide upon which to position the bottom surface of the last in the operation of the machine, as well as to protect the last from the action of the cutter, and the member 26 is shaped to serve the same purpose for the lateral surfaces of the last so as to present the insole with its edge transverse to the periphery of the cut-

ter or, in other words, transverse to the direction of cut. This relation is shown in Fig. 3 where 30 indicates a portion of a last and 32 an insole attached to the last and in position to be trimmed. By adjustment of the bracket 16 in the guideway 12 the position of the guide 26 with reference to the cutter may be varied, which obviously will serve to vary the extent of the trimming action of the cutter with reference to the lateral surfaces of the last. The plate 24 is also adjustable endwise on the bracket 16 and is held in adjusted position by means of a clamp 34. The purpose of this adjustment of the plate will be subsequently explained.

Carried by the bracket 18 is a plate 36 which is shaped at its end adjacent to the cutter to provide a support for the bottom face of the insole near its edge and to serve as a shearing member in coöperation with the edges of the cutter. The plate, in order to perform its function effectively, should be located closely adjacent to the periphery of the cutter, and adjustment of the plate in this respect is effected by adjustment of the bracket 18 in the guideway 14. The plate may thus be brought nearer to the cutter as the latter wears away and consequently decreases in diameter. The plate 36 is also adjustable endwise in relation to the bracket 18, and a screw 38 is provided to limit and determine its position in this respect. The plate 36 is held in position by the clamping effect of a bracket member 40 which is secured upon the front of the bracket 18. This member is provided with a socket in which is mounted a plunger 42 that is shaped at its forward end to serve as an additional rest for the work and has a rearward extension 44 that slides freely through the bracket. A spring 46 tends to urge the plunger forwardly toward the work, and a nut 48 threaded adjustably upon the extension 44 serves to limit the extent of forward movement of the plunger.

The parts thus far described provide a casing around the side and bottom portions of the cutter, and a shield 50 attached to the member 18 incloses the cutter at the top, thus serving to retain the chips and dust; while the member 18 is shaped to provide a conduit 52 that leads to a suction fan or similar device commonly used with this class of machines.

In the operation of the machine, the workman takes a last upon the bottom of which is attached an insole, and presents the insole to the cutter by resting the lateral and bottom surfaces of the last respectively upon the guides 26 and 28, with the lip 28 projecting between the insole and the bottom of the last. Since the bottom of the last is curved somewhat toward the edges of the heel seat and the insole is usually attached to

the heel portion of the last by a single tack near the center of the heel seat, the lip 28 may be inserted without bending the insole to any great extent. The plates 24 and 36 5 will have been previously adjusted relatively so as to provide sufficient space between the lip 28 and the end of the plate 36 to receive the work. This will depend, of course, principally upon the thickness of the stock, and 10 also to some extent upon the position of the plunger 42, which serves as a supplemental rest for the insole and last and determines, as will be evident from an inspection of Fig. 3, the angle of the face of the work with 15 reference to the cutter and consequently the degree of bevel formed upon the edge.

With the work positioned as described, the operator turns the last, keeping the latter in contact with the guides 26 and 28, and the 20 insole also in contact with the rest 42, so as to present all portions of the edge of the heel seat to the action of the cutter. He may begin the operation at the rear of the heel, and trim in both directions therefrom toward the shank, or may, as is usual, begin at one 25 side and trim around the heel to the other side. In either case it is advantageous and usually necessary, in order to cut inward to the extent required when trimming at the 30 side of the heel seat near the shank, to depress the plunger 42 somewhat when trimming at these points and turn the last about its longitudinal axis, thereby projecting the insole farther toward the cutter. This serves 35 at the same time to produce a longer bevel at the edges near the shank portion, which is a desirable feature, since the insole is often beveled in this manner by a special operation in order to secure a better fit for the 40 upper. With the shaft arranged, as shown, the operator is enabled to turn the last in a substantially vertical plane, which is advantageous in respect to facility in handling the last and to convenience in inspecting the 45 work. The forward inclination of the shaft provides space for the last to be turned downward to the necessary extent without interfering with any portion of the framework of the machine, while at the same 50 time, in view of the peripheral shape of the cutter head, the last will be substantially in a horizontal position when the cutter is operating at the rear of the heel, and the necessary turning movement will carry the last 55 equal distances above and below the horizontal.

Either of the plates 24 and 36, or both, 60 may be adjusted to provide the proper space for the insertion of the insole. It is usually preferable, however, first to secure the plate 36 in proper position with reference to the cutter to perform effectively its function as a shearing member and to make subsequent 65 adjustments of the plate 24 with reference thereto. The nut 48 will be turned so as to

bring the rest 42 to the proper position to secure the desired degree of bevel, and finally the bracket 16 will be adjusted so that the guide member 26 may position the last at the proper distance from the periphery of the 70 cutter to effect a cut of the desired inward extent. It is usually preferable to trim the blank so that its edges may lie flush with the lateral surfaces of the last.

With a machine constructed as described 75 the trimming operation will be effected smoothly and accurately, and a bevel will be formed on the edge without special attention on the part of the operator. With the cutter operating in the described manner there 80 will be no tendency to twist the blank on the last and consequently to cut inward too far in some portion, and the arrangement of the shearing member in coöperation with the cutter assures a clean cut without any tendency 85 to leave the edges ragged.

Although I have disclosed my invention as embodied in a machine having the particular 90 described features of construction, it will be understood that it is not limited to these precise details but that other embodiments are comprehended within the spirit and scope thereof as defined in the claims.

Having described my invention what I 95 claim as new and desire to secure by Letters Patent of the United States is the following:

1. A machine for trimming an insole attached to the bottom of a last comprising a driven cutter, and means upon which to position both the lateral and bottom surfaces of the last to present the insole in operative relation to the cutter, said means being arranged with reference to the cutter to cause the cutter to cut through the insole substantially in the direction of the height of the last and including a device constructed to extend between the bottom surface of the last and the insole and of such length and thickness as to hold the insole away from the last and prevent interference between the last and the cutter.

2. A machine for trimming an insole attached to the bottom of a last comprising a rotary cutter, and guiding means upon which to position the lateral and bottom surfaces of the last so as to present the insole with its edge transverse to the periphery of the cutter, said means being adjustable toward and from the periphery of the cutter so as to vary the depth of the cut with reference to the lateral surfaces of the last.

3. A machine for trimming an insole attached to the bottom of a last comprising a 125 rotary cutter, guiding means upon which to position the lateral surfaces of the last to present the insole to the action of the cutter, additional means coöoperating with said guiding means to protect the last from con- 130

tact with the cutter, and means for supporting the insole in the path of the cutter, all of said means being so arranged with reference to the cutter that it cuts through the 5 insole in a direction from one face to the other thereof.

4. A machine for trimming an insole attached to the bottom of a last comprising a rotary cutter, a guide member close to the 10 periphery of the cutter upon which to position the lateral surfaces of the last so as to present the insole with its edge transverse to the periphery of the cutter, said member having a lip in position to project between 15 the bottom of the last and the edge of the insole to guide the bottom surface of the last, and a member arranged to support the other side of the insole close to the periphery of the cutter.

5. A machine for trimming an insole attached to the bottom of a last comprising a driven cutter, means upon which to position both the lateral and bottom surfaces of the last to present the insole in operative 20 relation to the cutter, and a shearing member in position to contact with the outer face of the insole and coöperating with said cutter and 25 positioning means to trim the edge of the insole to a predetermined relationship to the 30 lateral surfaces of the last.

6. A machine for trimming an insole attached to the bottom of a last comprising a rotary cutter, guiding means upon which to position the last so as to present the insole 35 with its edge transverse to the periphery of the cutter, and a shearing member close to the periphery of the cutter and in position to support the edge of the insole during the 40 operation of the cutter.

7. A machine for trimming an insole attached to the bottom of a last comprising a rotary cutter, guiding means upon which to position the last so as to present the insole with its edge transverse to the periphery of 45 the cutter, and a shearing member close to the periphery of the cutter and in position to support the edge of the insole during the 50 operation of the cutter, and said shearing member being adjustable toward and from the periphery of the cutter.

8. A machine for trimming an insole attached to the bottom of a last comprising a rotary cutter, guiding means upon which to position the last so as to present the insole 55 with its edge transverse to the periphery of the cutter, and a shearing member close to the periphery of the cutter and in position to support the edge of the insole during the 60 operation of the cutter, said shearing member and guiding means having provision for relative adjustment toward and from each other.

9. A machine for trimming an insole attached to the bottom of a last comprising a

driven cutter, means upon which to position 65 the lateral surfaces of the last to present the insole in operative relation to the cutter so as to cause the latter to cut through the insole in a direction from one face to the other thereof, said means having a lip formed to 70 project between the last and the insole to serve as a guide for the bottom surface of the last, and a shearing member close to the path of movement of the cutter and located 75 opposite to said lip so as to support the outer side of the insole, said lip and shearing member having provision for relative adjustment to vary the distance between them.

10. A machine for trimming an insole attached to the bottom of a last comprising a driven cutter, means upon which to position both the lateral and bottom surfaces of the last to present the insole in operative relation to the cutter so as to cause the latter to 80 cut through the insole in a direction from one face to the other thereof, and additional 85 positioning means for determining the normal angle between the bottom surface of the last and the path of movement of the cutter. 90

11. A machine for trimming an insole attached to the bottom of a last comprising a driven cutter, guiding means close to the cutter upon which to position the lateral and bottom surfaces of the last so as to 95 cause the cutter to cut through the insole in a direction from one face to the other thereof, and a rest upon which to position the outer face of the insole to determine the normal angular relation of the bottom surface of the last to said guiding means, said 100 rest having provision for yielding movement to permit the operator to vary said angular relation.

12. A machine for trimming an insole 105 attached to the bottom of a last comprising a rotary cutter, guiding means upon which to position the lateral and bottom surfaces of the last so as to present the insole with its edge transverse to the periphery of the 110 cutter, and additional means upon which to position the face of the insole to determine the normal angular relation of the bottom surface of the last to said guiding means and the consequent angle between the 115 face of the insole and the path of movement of the cutter.

13. A machine for trimming an insole attached to the bottom of a last comprising a rotary cutter, guiding means upon which to position the lateral and bottom surfaces of the last so as to present the insole with its edge transverse to the periphery of the cutter, and additional means upon which to position the insole to determine the normal angle between the face of the insole and the path of movement of the cutter, said additional means having provision for yield- 125

ing movement to permit the operator to vary said angle and consequently the degree of bevel on the insole edge.

14. A machine for trimming an insole attached to the bottom of a last comprising a rotary cutter, guiding means upon which to position the lateral and bottom surfaces of the last so as to present the insole with its edge transverse to the periphery of the cutter, and a rest upon which to position the outer face of the insole to determine the normal angular relation of the bottom surface of the last to said guiding means and the consequent angle between the face of the insole and the path of movement of the cutter, said rest being adjustable to vary said angle and consequently the degree of bevel on the insole edge.

15. A machine for trimming an insole attached to the bottom of a last comprising a shaft inclined upwardly and forwardly toward the front of the machine, a rotary cutter mounted on said shaft, and guiding means upon which to position the lateral and bottom surfaces of the last to permit turning movement of the last in a substantially vertical plane to present the insole to the action of the cutter, said means being constructed to maintain out of contact with the last all portions of the insole which are within the range of action of the cutter.

16. A machine for trimming an insole attached to the bottom of a last comprising a shaft inclined from the vertical toward the front of the machine and having at its upper end an upwardly tapering frustoconical cutter formed with cutting edges across its periphery, and guiding means at

the front of the cutter upon which to position the lateral and bottom surfaces of the last so as to present the insole for turning movement in a substantially vertical plane transverse to the periphery of the cutter.

17. A machine for trimming an insole attached to the bottom of a last comprising a rotary cutter, guiding means upon which to position the lateral surface of the last to present the insole to the cutter with its edge transverse to the direction of cut, and means constructed and arranged with reference to said guiding means to project inwardly over the last bottom between the last and the insole and to extend substantially across the periphery of the cutter to determine the position of the bottom surface of the last with reference to the cutter.

18. A machine for trimming an insole attached to the bottom of a last comprising a rotary cutter, a guide member close to the periphery of the cutter upon which to position the lateral surface of the last to present the insole to the cutter with its edge transverse to the direction of cut, and a lip on said guide member formed to project inwardly between the bottom of the last and the insole opposite to substantially all portions of the insole which are within the range of action of the cutter.

In testimony whereof I have signed my name to this specification in the presence of two subscribing witnesses.

JOHN B. HADAWAY.
